C. E. KINNARD.

AUTOMATIC SAFETY DEVICE AND DANGER ZONE SIGNAL.
APPLICATION FILED AUG. 4, 1917.

1,246,434.

Patented Nov. 13, 1917.

UNITED STATES PATENT OFFICE.

CHARLES E. KINNARD, OF COCHRAN MILLS, PENNSYLVANIA.

AUTOMATIC SAFETY DEVICE AND DANGER-ZONE SIGNAL.

1,246,434.

Specification of Letters Patent. Patented Nov. 13, 1917.

Application filed August 4, 1917. Serial No. 184,374.

To all whom it may concern:

Be it known that I, CHARLES E. KINNARD, a citizen of the United States, residing at Cochran Mills, in the county of Armstrong,

5 State of Pennsylvania, have invented a new and useful Automatic Safety Device and Danger-Zone Signal; and I do hereby declare the following to be a full, clear, and exact description of the invention, such as 10 will enable others skilled in the art to which it appertains to make and use the same.

The present invention relates to an automatically operated railway gate, and has for its object to provide a device of this 15 character which embodies novel features of construction whereby a set of gates, a danger zone signal, or other safety device, can be positively and effectively operated by the rolling stock.

20 Further objects of the invention are to provide an automatically operated railway gate which is comparatively simple and inexpensive in its construction, which provides an effective means for opening and closing 25 the gates without the use of an electric current and electric motors, which is not liable to get out of repair, and which will open and close the gates automatically at the proper intervals of time.

30 With these and other objects in view, the invention consists in certain novel combinations and arrangements of the parts as will more fully appear as the description proceeds, the novel features thereof being 35 pointed out in the appended claims.

For a full understanding of the invention, reference is to be had to the following description and accompanying drawings, in which:—

40 Figure 1 is a top plan view of a railway crossing provided with an automatically operated gate constructed in accordance with the invention.

Fig. 2 is a side elevation of the same.

45 Fig. 3 is an enlarged side elevation of one of the trip plate controlled gate operating devices.

Fig. 4 is a transverse vertical sectional view on the line 4—4 of Fig. 3.

50 Corresponding and like parts are referred to in the following description and indicated in all the views of the drawings by the same reference characters.

Referring to the drawings, which illustrate one embodiment of the invention, the 55 reference characters A and B designate a

pair of standard railroad tracks which are arranged side by side, the trains moving from left to right traveling upon the track A, while the oppositely moving trains travel 60 upon the track B. A crossing is indicated at C, and a pair of gate standards 1 is arranged upon each side of the crossing, one set of gates 2 being pivotally mounted at 3 upon the upper ends of one pair of gate 65 standards, while a cooperating set of gates 4 are pivotally mounted at 5 upon the upper ends of the other pair of gate standards. The respective gates are counter-weighed at 2^a and 4^a respectively so that they can be 70 very easily swung about their pivot points into either an open or a closed position. Arranged under each of the gates is a gate operating lever 6 which is pivotally mounted at 7 upon the standard 1 and extends in- 75 wardly toward the crossing C. A spring arm 14 is secured to the lower side of each of the levers 6 and extends rearwardly beyond the pivot point 7 thereof, said spring arms having the operating cables connected 80 thereto and serving as shock absorbing means to avoid a jerky movement of the gates and enable them to be opened and closed with a smooth even movement. The swinging end of each of the levers 6 is connected by a diagonal link 8 to the counter-weighted end of the respective gate, so that by swinging the levers the gates can be moved up and down. Owing to the fact that the links 8 are diagonally disposed and 85 connected to the gates and levers on opposite sides of the standards 1, it will be obvious that the respective gates and levers will 90 swing in opposite directions.

The gate standards 1 of each pair of gates 95 are connected at the bases thereof by a pair of horizontally disposed transverse shafts 9 and 10, said shafts extending under the tracks and being provided at the ends thereof with the respective pulleys 11 and 12. 100 The operating levers 6 for the gate 2 have cables 13 secured to the ends thereof to which the diagonal links 8 are connected, said cables passing down and around the pulleys 12 of the shaft 10 on the corresponding side 105 of the road, across the road and around the pulleys 11 of the shaft 9 on the opposite side of the road, and thence upwardly to the springs 14 of the operating levers 6 for the gates 4. The two sets of gates 2 and 4 are 110 thus operatively connected with each other so as to be raised and lowered in unison.

Trip controlled operating devices D and E are applied to the rails of the respective tracks A and B on opposite sides of the crossing C. These trip controlled devices 5 are substantially identical in construction, so that a description of one will apply to both of them. Each of these devices includes a vertically disposed elongated trip plate 15 which is arranged at the outside of one of 10 the track rails, so as to be engaged by the wheel treads of the rolling stock, and is mounted to have both an up and down movement and a longitudinal sliding movement. The upper edges of the trip plates are 15 beveled toward opposite ends thereof, as indicated at 15^a, so that the wheel treads will have a gradual engagement therewith, and the ends of the trip plates have leaf springs 16 secured thereto, said springs projecting 20 longitudinally in opposite directions and being offset downwardly so as to provide yieldable supports for the trip plates and normally hold them up in operative position, although the plates are adapted to be forced 25 downwardly by the wheels of the rolling stock when a train travels along the track. The lower edge of each of the trip plates 15 is received within the vertical guide slots 17^a of a series of blocks 17 which are secured to the projecting ends of the track ties A. The inner faces of the guide blocks 17 are cut away and shaped to fit over the basal flanges and within the fishing space of 30 the rail, as indicated at 17^b, while the outer 35 faces of the guide blocks are formed with flanges which extend over the projecting ends of the ties A and are spiked or otherwise rigidly secured thereto, as indicated at 17^c. Each trip plate 15 is thus free to move 40 up and down and also to slide longitudinally within the slotted portions 17^a of the guide blocks 17, being normally held resiliently in a raised position by the springs 16, and being limited in its movements by pins 18 extending 45 across the guide slots 17^a of certain of the guide blocks, and received loosely within triangular openings 19 in the trip plate, said openings being sufficiently large to provide for the necessary movements of 50 the trip plates, and the pointed lower ends of the openings coöoperating with the pins 18 and the springs 16 to bring the trip plates back into correct operative position 55 as soon as they are out of engagement with the wheels of the rolling stock.

The lower edge of the trip plate 15 is shown as cut away or notched at 20 for engagement with the end 21 of a crank member 22 which projects from one end of a rock 60 shaft 23 arranged at one side of the track and extending transversely with respect thereto. One end of the notch 20 is deeper than the other end, and when a train is moving upon the track in a direction toward

the crossing C the longitudinal movement 65 of the trip plate 15, which will be in the same direction as that in which the train is moving, will cause the crank arm 21 to be engaged by the shallow end of the notch 20, with the result that the transverse shaft 23 70 will be rotated. However, should a train be moving in the opposite direction, the longitudinal movement of the trip plate 15 will bring the deep end of the notch 20 over the crank member 22, with the result that the 75 movements of the trip plate will not swing the crank member and rotate the rock shaft 23. The construction is thus such that a train moving upon the track toward the crossing C will actuate the trip plate 15 in 80 such a manner as to bring about a rotation of the rock shaft 23, although a train moving in the opposite direction will not cause a rocking movement of the said shaft. This rock shaft 23 is connected by the gearing 24 85 to a countershaft 25 which is provided with a drum 26, the two transverse shafts 23 and 25 being journaled upon bars 28 which extend longitudinally of the track and are secured to the ends of the ties A at one side of 90 the track rails.

A train approaching the crossing C on the track A will operate the trip controlled device D and produce a pull upon a gate closing cable 27 which is connected to the drum 26 of the operating device D. This cable 27 extends along the sides of the track A to the crossing, where it passes around one of the pulleys 11 of the transverse shaft 9 and is carried upwardly to the spring arm 14 of 100 the operating lever for one of the gates 2. The corresponding pulley 11 at the opposite end of the shaft 9 for the gates 2 is connected by a cable 27^a to the spring arm 14 of the lever 6 for the said gate. It will thus be 105 obvious that when the device D is actuated by the passage of a train over the same, the gate closing cable 27 will be wound upon the drum 26, and a pull thereby produced upon the spring arms 14 of the levers 6 for 110 the gates 2, with the result that the gates 2 will be lowered into a closed position. As has been previously described, the gates 2 are operatively connected to the gates 4, in such a manner that both sets of the gates 115 will swing downwardly into a closed position at the same time. After the train has passed over the trip controlled device D, the counter-weights upon the gates will cause them to swing slowly into an open 120 position, although in the meantime the train will have completely passed over the crossing.

A train moving in the opposite direction upon the other track B will actuate the trip 125 controlled device C, the pulley 26 of which is connected by a cable 30 which extends longitudinally of the track, around the

pulley 10 of the corresponding gate 4, and upwardly to the spring arm 14 of the lever 6 for the said gate 4. The gates 2 and 4 will thus be closed by the actuation of the 5 device C, and after the train has passed over this device C the counter-weights upon the gates will cause them to swing slowly into an open position, although the train will have passed beyond the crossing before 10 the gates reach an upright position.

Having thus described the invention, what I claim as new and desire to secure by Letters Patent, is:—

1. An automatic railway gate including a 15 vertically disposed trip plate arranged at the outside of one of the track rails and mounted to have both an up and down and a longitudinal sliding movement when engaged by the wheel treads of the rolling 20 stock, slotted guide blocks receiving the trip plate to direct it in its movements, a rock shaft extending transversely of the track and provided with a crank portion which is operatively connected to the trip 25 plate, a counter-shaft geared to the rock shaft, a drum upon the countershaft, a gate, and a cable operatively connecting the gate and the drum.

2. An automatic railway gate including a 30 vertically disposed trip plate arranged at the outside of one of the track rails and mounted to have both an up and down and a longitudinal sliding movement when engaged by the wheel treads of the rolling 35 stock, slotted guide blocks receiving the lower edge of the trip plate to direct it in its movements, springs normally moving the trip plate upwardly into operative position, stop means limiting the upward movement 40 of the trip plate, a rock shaft extending transversely of the track and provided with a crank portion which is operatively connected to a trip plate, a countershaft geared to the crank shaft, a drum upon the counter-

shaft, a gate, and a cable operatively connecting the drum and the gate. 45

3. A railway gate including a gate standard, a guide pulley at the base thereof, a counter-weighted gate pivotally mounted upon the upper end thereof, an operating 50 lever arranged under the gate and pivoted upon the standard, a link member between the swinging end of the operating lever and the gate, a spring arm secured to the operating lever and extending rearwardly beyond the pivot thereof, and a cable connected to the spring arm and passing around the pulley at the base of the standard for operating the gate. 55

4. A railway gate including standards arranged upon opposite sides of the crossing, a pair of guide pulleys at the base of each of the standards, counter-weighted gates pivotally mounted upon the upper ends of the standards, operating levers arranged 60 under the respective gates and pivoted upon the standards, links connecting the operating levers to the respective gates, a cable passing around one set of pulleys at the bases of the standards and having the extremities thereof 65 operatively connected to the corresponding operating levers for causing the two sets of gates to move in unison, gate closing cables passing around one of the other pulleys of each set of the gates and operatively connected to the corresponding lever for closing the gates, cables connecting the remaining pulleys to the operating levers of the corresponding gates, and means for pulling 70 upon the gate closing cables. 75

In testimony whereof I have signed my name to this specification in the presence of two subscribing witnesses.

CHARLES E. KINNARD.
